UNITED STATES PATENT OFFICE.

GEORGE A. LOWRY, OF NEW YORK, N. Y., ASSIGNOR TO JOHN J. FEUGE AND L. RICHMOND BROWNE, BOTH OF NEW YORK, N. Y.

MEANS FOR CLEANING FIBROUS MATERIALS.

Application filed September 6, 1924. Serial No. 736,264.

To all whom it may concern:

Be it known that I, GEORGE A. LOWRY, a citizen of the United States, residing at New York, county of New York, and State of New York, have made a certain new and useful Invention in Means for Cleaning Fibrous Materials, of which the following is a specification.

This invention relates more particularly to a fiber cleaning and fiber preparing machine which is designed and adapted to efficiently and economically handle flax, ramie, hemp and other fiber producing plants for the purpose of expeditiously removing the woody portions from the fiber and at one and the same time obtaining the full fiber or reed for long spinning units or threads; another object of my invention includes the production of a machine of the type described which is inexpensive to manufacture, easily and economically operated and which can be readily transported and quickly placed in readiness for operation.

A further object includes the production of a safe but sufficient machine for the preparation of flax and other fiber suitable for spinning units, for weaving and for other purposes.

Other objects will appear hereinafter and I attain these objects by the machine illustrated in the accompanying drawings, in which:

Fig. 1 is a view in side elevation of a machine embodying the principles of my invention.

Fig. 2 is an end elevation thereof.

Fig. 3 is a view showing the rack bar and operating mechanism.

Fig. 4 is a plan view thereof.

Fig. 5 is an end view thereof.

Fig. 6 is an enlarged detail showing an end view of the fiber cleaning and subdividing elements with a portion of the operating mechanism removed.

Fig. 7 is a view taken on the line 7—7 of Fig. 5, and

Fig. 8 is a somewhat diagrammatic representation showing the first contact of the fiber in the cleaning and subdividing units.

Like numerals refer to similar parts throughout the several views.

It is among the prime purposes of my invention to provide a simple and inexpensive machine which will clean the fiber of flax,

and the like, by finely subdividing or breaking the woody portion of the stalk without damaging or greatly disrupting the fiber. This is accomplished by a series of fluted rolls operating in pairs and so arranged or constructed that the stalks are bent or folded together transversely of the direction of travel of the material. By this action the bent or broken woody pieces receive end-on crushing action of the rolls, which action causes the broken woody pieces or chives to be loosened or stripped and pushed out of the fiber portion in the manner set forth in my co-pending application, Serial No. 736,265 of even date herewith, for method of cleaning and preparing fibrous materials. The chives thus loosened readily drop out of the fiber bundle during the last stage of operation, and they are readily shaken out by hand or by beaters. No violent beating is required, however, for this purpose and the fiber mass is found to remain in contact as long ribbon-like threads. The machine is arranged to be operated by foot-power of the two attendants who operate it, or it may be operated by any suitable motive power, if desired.

As a practical embodiment of my invention, to which, however, I do not desire to be limited, I provide pairs of intermeshing and interlocking operating units, 10, 10¹, 11, 11¹ and 12, 12¹. These units comprise solid rolls which are rotatably mounted on suitable journals 13, 13, 14, 14 and 15, 15, and which journals operate in bearings 16, 16, 17, 17 and 18, 18. These bearings are supported on crossbars 21 of the supporting frame 22 and are in pairs. One set of these bearings, namely those for supporting rolls 10, 11 and 12, fixedly hold the journals, while its company bearings for rolls 10¹, 11¹ and 12¹ are provided each with a slot 23 in which is held member 24 by springs 25. By this construction one of each of the pairs of rolls is fixed while its companion roll is movable laterally and is held by a tension spring 25. Each spring 25 is properly tensioned by a tension screw 26 which presses against a tension block 27. The rolls are provided with fluted surfaces or ribs 20, 20 which intermesh in a particular manner to be more fully described below and the fixed rolls are provided with means for giving a positive rotative back and forth movement for

operating on the fibrous materials. In its simplest form the power is from foot treadles 28, which are mounted on the crank arm 29 to one end of which is a crank lever 5 30. This lever is connected with a bell crank 31 which in turn is fastened on a journal 32. The journal is properly supported in bearings 33 on a cross beam 34 of the main frame. Journal 32 carries also the 10 beater drive pulley or sprocket wheel 35 and the transmission crank 36. To crank 36 is attached the pitman 37 for driving the rack bar 38. This bar slides back and forth in its rack frame 39 which is fastened by suitable pins 40 to the supporting frame members 21.

Rack bar 38 is provided with gear teeth 41 which mesh with the gear teeth 42 of the gear wheel 43. This gear wheel is loosely 20 mounted on journal 15 and carries on either face a pivotally mounted dog 44 and 45. These dogs are disposed in opposite directions and are held in depressed position by suitable means as tension springs 46 and 25 47 for the purpose of engaging their respective ratchet wheels 48 and 49. The ratchet wheels 48 and 49 are both fastened to journal 15 and cause the same to rotate when 30 the respective ratchets become effective by reason of the to and fro movement of the rack bar and consequently also gear 43. It will be noted that dog 44 is free to engage its corresponding ratchet wheel 48 whenever the 35 rack bar 38 is moved downwards, while its companion dog 45 is effective only for a portion of the upward movement of the rack bar 38 as it returns to its initial position. This ineffective action is caused by pin 50 40 on dog 45 meeting and riding on cam 51 to be raised out of engaging position for approximately one-half of the return stroke. The combined action of the two dogs and 45 associated elements will accordingly cause the gear wheel 43, and therefore also its journal and attached roll, to rotate approximately half a revolution with each down stroke of the rack bar 38, while the return or upward stroke of said bar, due to the cam action, is effective for only a quarter return or backward 50 rotation.

This motion is imparted to the companion rolls as follows: The flutings of roll 12 engage the flutings of roll 12¹ and therefore will cause the forward half turn and the backward quarter turn of roll 12 to be imparted to roll 12¹ and in so doing the opposite sides of the flutings will press against the respective offered sides of the flutings of its companion roll and thereby cause 60 special splitting action on the fiber, as will be more fully discussed in my companion application of even date herewith.

To impart the oscillatory backward and forward movement of the drive roll to the companion rolls above, any suitable means

may be provided. To this end I have provided a sprocket 52 on which chain 53 rides and imparts its motion to a sprocket 54 on journal 14, to thereby cause its roll 11 to move in unison with the initial drive 70 sprocket and its roll 12. Roll 11 imparts its movement to roll 11¹ in the same manner and for a like purpose that roll 12 acts on roll 12¹. Likewise journal 14 of roll 11 carries a second drive sprocket 55 on which 75 56 rides and imparts its motion to sprocket 57 on journal 13 of the first roll 10, and roll 10 imparts its motion to its companion roll 10¹ in the manner stated above for the initial drive roll 12 and its companion 12¹. 80

Beaters 60 are mounted in a convenient position and are driven by a belt or chain 61 from the drive pulley or sprocket 35 and a fly wheel 62 maintains a uniform motion of the machine. 85

The machine is further provided with a hood 63, having a hopper 64 into which the fibrous plants are fed through the elongated opening 65 in the feed guide 66.

From the description given above, the operation will be readily understood and is as follows:

Where the machine is operated by foot power, an operator is stationed in front of the machine, or to the left of Fig. 1. This operator feeds the fibrous plants into the hopper 64 and at the same time places his foot on the end of his treadle 28 to move the same up and down. A second operator for receiving and removing the treated and cleaned fiber stands or sits to the right of the machine (Fig. 1) and he likewise applies his foot to his end of the treadle 28 to assist in the operating of the machine. This action is well understood and as the rack bar is thus caused to move up and down, it imparts its full downward stroke to gear 43 which imparts its movement through dog 44 to the ratchet wheel 48. This in turn is caused to rotate and with it all the rolls move through approximately half a revolution in unison. This movement causes the material to be forced between the flutings 20 and the woody material is thereby broken or cracked at somewhat regular intervals in somewhat the manner illustrated in Fig. 8. With the return or upward stroke, however, of the rack bar and its gear, dog 44 is ineffective, but its companion 45 becomes operative, owing to the opposite position. Because of the cam 51, however, dog 45 will be lifted out of engagement at the desired interval and for the proper time so that the rolls will all be reversed in unison at such a time as is most effective. In practice I have found that for 100 flax a quarter reverse motion is ample to properly bend and crowd together the stalk and fiber sections. This quarter return motion is then succeeded by a half forward movement of all the rolls which action now 105 110 115 120 125 130

in rolls 10, 10¹ and 11, 11¹ removes the broken woody parts of the plant by end on pressure as it were, and at the same time causes a most desirable action on the fibers themselves in the production of the full reed without much rupturing and splitting action. As the forward and backward action continues, the entire stalk or bundle of stalks is fed through the machine and comes out below onto the receiving pan 67, to be there taken by the receiving operator and subjected to the beater 60, to fully and completely finish the cleaning process and to draw out and straighten the crumpled fibers. Fibers thus cleaned and straightened are of a high grade for obtaining very long threadlike structure with very little or no loss of fiber as tow in the cleaning operation.

Having now described my invention, what I claim as new and useful, of my own invention, and desire to secure by Letters Patent is:

1. In a machine for cleaning the woody part from the fibrous part of plant stalks, the combination of a plurality of members rotatably mounted in pairs, means for causing said members to move periodically in one direction alternated with intermittent movement of said members in the other direction, the relative movement of said pairs of rolls being such as will cause the plant stalk to be folded transversely of its forward movement, to be then subjected to end-on breaking or disruptive action of said successive rolls to strip the chives out of the fiber material.

2. In a machine for removing the woody parts from the fibrous parts of plant stalks, the combination of a plurality of members mounted to rotate in unison in either direction, and means to cause said members to rotate positively in one direction alternated with intermittent reverse movement in the opposite direction, said movement in the opposite direction being less than the movement in the forward direction, whereby the plant stalks are broken and folded to thus subject the folded stalk to the disruptive action of successive rolls for the removal of the chives.

3. In a machine for cleaning the woody part from the fibrous part of plant stalks, the combination of a plurality of members mounted to rotate in unison in either direction, and means to cause said members to rotate positively in one direction alternated with intermittent reverse movement in the opposite direction, said positive movement in one direction being approximately twice the distance of movement in the reverse direction, whereby the stalk is broken and folded to receive a disruptive action from successive rolls for freeing said broken woody parts from the fiber.

4. In a machine for eliminating the woody

part from the fibrous part of plant stalks, the combination of a plurality of fluted rolls mounted in pairs, the flutings of each pair of rolls interlacing and being of successive varying sizes for each pair of rolls, drive members connected to one member of each pair, and means for causing one of said connected members to move half a turn forward intermittent with a quarter of a turn backward to fold and break the plant stalk and to subject the bent or broken portions of the woody stalk to end-breaking.

5. In a machine for removing the woody portion from the fibrous part of plant stalks, the combination of a plurality of fluted rolls mounted in pairs, the flutings of each pair of rolls interlacing and being of successive varying sizes for each pair of rolls, drive members connected to one member of each pair and means for causing one of said connected members to move half a turn forward intermittent with a quarter of a turn backward, to thereby act repeatedly on the fibrous material to break the woody portion and fold the same and to feed said folded portion to successive rolls, and means to supply said material to said rolls.

6. In a machine for cleaning fibrous plant stalks of the woody part, the combination of a plurality of fluted rolls mounted in pairs, means to operate said rolls at the same speed, and means to cause the plant stalks to be folded whereby the folded parts are subjected to end-on disruptive actions of successive rolls.

7. In a machine for freeing the woody part from the fibrous part of plant stalks, the combination of a plurality of fluted rolls mounted in pairs, the flutings of each pair of rolls interlacing and being of successive varying sizes for each pair of rolls, drive members connected to one member of each pair and means for causing one of said connected members to move half a turn forward intermittent with a quarter of a turn backward, to cause the plant stalk to be folded and the woody part to break and receive disruptive end on action of successive rolls.

8. In a machine for cleaning flax, the combination of a plurality of fluted rolls mounted in pairs to rotate at uniform speed, means to adjust one of each of the pair of rolls and driving means for the other of said pair of rolls whereby said rolls are caused to move in unison, a gear mounted to move back and forth, and means carried by said gear for causing its motion to be fully transmitted to said rolls in one direction, and means associated with said gear for causing its motion to be only partially transmitted to said rolls in the reverse direction, whereby the flax material is folded upon itself and is then subjected to end-on crushing.

9. In a machine for cleaning and treating fibrous materials, a plurality of members ro-

- tatably mounted, means for causing said members to move periodically in one direction alternated with intermittent movement of said members in the other direction and 5 a reciprocating rack bar for operating said means whereby the fibrous material is folded upon itself and is then subjected to end-on crushing action of successive pairs of rolls.
10. 10. In a machine for freeing the woody part from the fibrous part of plant stalks, the combination of a plurality of fluted rolls mounted in pairs, the flutings of each pair of rolls interlacing and being of successive 15 varying sizes for each pair of rolls, drive members connected to one member of each pair and means for causing one of said connected members to move half a turn forward intermittent with a quarter of a turn backward, to cause the plant stalk to be folded and the woody part to break and receive disruptive end-on action of successive rolls, and means to cause the broken chives to be 20 dislodged.
25. 11. In a machine for cleaning and treating fibrous materials, a plurality of fluted rolls mounted in pairs and having their flutings intermeshing, adjusting means for one of each roll of said pairs of rolls and 30 drive means for the other of each of said pairs of rolls, a rack bar, power means to
- drive said rack bar, a gear wheel co-operating with said rack bar, dogs on said gear, a ratchet member for each dog, said ratchet members being in positive connection with one of the drive rolls and having their effective teeth extend in opposite directions, whereby but one dog becomes effective as the gear moves forward and backward in unison with the rack bar. 35
40. 12. In a machine for cleaning and treating fibrous materials, a plurality of fluted rolls mounted in pairs and having their flutings intermeshing, adjusting means for one of each roll of said pairs of rolls and drive means for the other of each of said pairs of rolls, a rack bar, power means to drive said rack bar, a gear wheel co-operating with said rack bar, dogs on said gear, a ratchet member for each dog, said ratchet members 45 being in positive connection with one of the drive rolls and having their effective teeth extend in opposite directions, whereby but one dog becomes effective as the gear moves forward and backward in unison with the rack bar, and means for rendering one of the dogs ineffective during a portion of said movement. 50
55. In testimony whereof I have hereunto set my hand on this 25th day of August A. D. 60 1924.

GEORGE A. LOWRY.
